UNITED STATES PATENT OFFICE

120,481

DESIGN FOR A GARMENT CLEANING UNIT

Carl Dahlberg, Duluth, Minn.

Application January 11, 1940, Serial No. 89,402

Term of patent 3½ years

To all whom it may concern:

Be it known that I, Carl Dahlberg, a citizen of the United States, residing at Duluth, in the county of St. Louis and State of Minnesota, have invented a new, original, and ornamental Design for Garment Cleaning Units, of which the following is a specification, reference being had to the accompanying drawing, forming part thereof.

In the drawing:

The figure is a perspective view of a garment cleaning unit, showing my new design, the other side of the unit being substantially plain.

I claim:

The ornamental design for a garment cleaning unit, as shown and described.

CARL DAHLBERG.
